UNITED STATES PATENT OFFICE.

CARL H. WERNER, OF WATERLOO, IOWA.

FLOOR-SURFACING MACHINE.

1,129,929.

Specification of Letters Patent.

Patented Mar. 2, 1915.

Application filed April 29, 1914. Serial No. 835,163.

To all whom it may concern:

Be it known that I, CARL H. WERNER, a citizen of the United States of America, and a resident of Waterloo, Blackhawk county, 5 Iowa, have invented certain new and useful Improvements in Floor-Surfacing Machines, of which the following is a specification.

This invention relates to improvements in machines for surfacing floors, and the object 10 of my improvement is to furnish a device of this kind which will satisfactorily smooth down the surface of a floor and which has its abrading mechanisms so arranged in order that they will act positively in the 15 process and be supplied with means for detachably securing abrading strips thereon for convenient replacement when desired. This object I have accomplished by the 20 means which are hereinafter described and claimed, and which are illustrated in the accompanying drawings, in which:

Figure 1 is a side elevation of my improved machine for surfacing floors, showing parts broken away. Fig. 2 is a horizontal section of the device shown in Fig. 1, 25 taken along the line A—B thereof. Fig. 3 is an end elevation of said machine, showing the parts broken away. Fig. 4 is a side elevation of one of the abrading mechanisms, 30 showing parts thereof vertically sectioned.

Similar numerals of reference denote corresponding parts throughout the several views.

My improved machine for surfacing 35 floors comprises a supporting frame which is built up from the spaced longitudinal side bars 19, having uprights 16 fixed to their opposite ends, and the upper ends of the latter are fixedly connected together by 40 means of the spaced transverse bars 17 and 18. The latter bars have their interspaces partially filled by means of the blocks 32, the ends of the latter being spaced apart to provide horizontal longitudinally extended 45 interspaces or slideways 31. The lower bar 18 is reinforced at its ends by means of angle plates 33 securing it to the side uprights 16. The uprights 16 are further supported by means of braces 20 extending from the 50 upper ends thereof to the side bars 19. Arch-bars 30 are placed longitudinally and secured at their ends to the upper parts of the transverse bars 17. Handles 29 are secured to said arch-bars, and the motor is 55 mounted upon one of them. Upwardly pro-

jecting plates 23 are secured to the middle parts of the side bars 19, and have bearings 24 secured upon their upper ends to receive the ends of a rotatable crank shaft 1, which is supplied with a plurality of oppositely 60 projecting cranks 2. A sprocket wheel 22 is secured upon one end of the shaft 1, and is driven by means of a sprocket chain 25 passed about a small pinion 27 secured on the driving shaft 26 of said motor 28. To 65 each of said cranks 2 is pivoted a pitman 3, and to each pitman is pivoted one end of the slide-bar 4, which latter is passed slidably through one of the slideways 31. Each slide-bar 4 has its outwardly projected end 70 bent downwardly and provided with pintles which are pivoted in lugs 5 located near one end of the top of the block 6.

Referring now to Fig. 4, it will be seen that another block 7 is located under the 75 block 6 to fit thereon, and that the opposite ends of said blocks are angularly grooved transversely along the line of their junction. In these grooves are seated detachable fitting strips 14 and 15, and a rectangular 80 clamp 9 is then placed about both blocks, covering their said line of junction and also the said strips as shown. One end of the said clamp is pivotally secured to the abutting end of the upper block 6 by means of 85 the hinge 10 so that the upper block may be swung free from said clamp upwardly when desired. The strip 14 is fixedly secured to said clamp, while the other strip 15 is detachable from the clamp at that end. 90 A thumb screw 11 is seated within a threaded orifice in the clamp 9 to bear against the strip 15. A strip of sand paper or other abrasive material 8 is then passed about the flat underface of the lower block 7 longitudinally, then passed upwardly over both ends of both the blocks 6 and 7 to be seated between them and the strips 14 and 15 within the said angular troughs or grooves. The thumb screw 11 is then moved to tighten 95 100 the said strips firmly against the ends of the abrasive strip to hold it securely in place.

The numeral 12 denotes oppositely directed studs or pins on the down-turned 105 end of each slide-bar 4, and springs 13 have their ends secured about said studs. The springs are preferably of looped form, having their looped ends seated upon the upper surface of the block 6 to exert a yielding 110

pressure thereon, and thereby tend to hold the block 7 level upon the floor to be surfaced with a yielding pressure, similar to a manual pressure. When it is necessary to 5 remove the abrasive strip 8, the blocks can be tilted upwardly on the pivots 5 against the yielding spring 13, the thumb screw 11 then loosened, and the upper block 6 swung upwardly, while the lower block 7 is drawn 10 downwardly, thereby releasing said strip 8. The blocks are then re-covered with another abrasive strip, whose ends are easily introduced into the troughs or grooves in said blocks, and secured therein by means of 15 the thumb screw 11 and the strips 14 and 15.

The machine is operated by pushing it by means of the handles 29 on the floor to be surfaced while the motor 28 is rotating the crank shaft 1 to reciprocate the said 20 abrasive mechanisms by the operative connections shown. The abrading mechanisms are located at opposite ends of the device, and are staggered in relation to each other which permits them to work upon a surface 25 where parts thereof are of slightly different levels and yet be able to impart a good polish thereto without missing any part of the surface. The supporting frame is preferably mounted upon the rollers 21 30 whereby it may be easily pushed about the floor. Any desired means may be adopted to rotate the crank shaft 1, and any desired number of abrading mechanisms may be used.

35 Having described my invention, what I

claim as new, and desire to secure by Letters Patent, is:

1. In a floor surfacing machine, the combination with a supporting frame having horizontal supporting slideways on opposite ends thereof, a rotary shaft mounted across said frame medially, and provided with oppositely-projecting cranks, pitmen connected to said cranks, downwardly curved arms pivoted to said pitmen and 40 slidably seated upon said supporting slideways, and abrading mechanisms mounted upon the outer downturned ends of said arms.

2. In a floor surfacing machine, the combination with a supporting frame having horizontal supporting slideways on opposite ends thereof, a rotary shaft mounted across said frame, and provided with a plurality of oppositely-projecting cranks, pitmen connected to said cranks, downwardly curved arms pivoted to said pitmen and 45 slidably seated upon said slideways, abrading mechanisms pivotally connected to the outer downturned ends of said arms, and yieldable resilient means connected to said arms and adapted to yieldingly bear against 50 said mechanisms to keep them in contact throughout with the surface operated upon.

Signed at Waterloo, Iowa, this 15th day 55 of April, 1914.

CARL H. WERNER.
